UNITED STATES PATENT OFFICE.

LA FAYETTE ALDRICH, OF MILWAUKEE, WISCONSIN.

STEAM-PIPE AND BOILER COVERING.

SPECIFICATION forming part of Letters Patent No. 308,943, dated December 9, 1884.

Application filed February 4, 1884. (No model.)

To all whom it may concern:

Be it known that I, LA FAYETTE ALDRICH, a citizen of the United States, residing at Milwaukee, in the county of Milwaukee and State of Wisconsin, have invented certain new and useful Improvements in Steam-Pipe and Boiler Coverings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in covering for steam-pipes and boilers, and pertains to that class which is formed in separate sections preparatory to being laid upon the pipe or boiler.

20 My improvements consist more especially in the device for holding the parts composing the several sections together and the manner of supporting the covering upon the steam-pipes or boilers at a distance therefrom.

25 The construction of my improvements is further explained by reference to the accompanying drawings, in which—

Figure 1 represents a cross-section of my covering attached to a steam-pipe. Fig. 2 illustrates the manner of connecting the sections of covering to a boiler. Fig. 3 represents the exterior of the covering upon a steam-pipe. Fig. 4 represents the interior view of the covering as made preparatory to being placed on a boiler.

Like parts are represented by the same reference-letters throughout the several views.

A represents the steam-pipe or boiler. B is a covering, consisting of sheet metal C, 40 layers of paper D, layer of felt E, layers of paper F, and sheet-metal interior G. This covering is retained in proper shape for handling preparatory to being placed upon pipes or boilers by a metallic frame formed of sheet-metal strips H and I, arranged at right angles and secured to each other and the covering by bolts J, as shown in Figs. 2 and 4.

K K are retaining-bands, and L L are binding-bolts, by which bands and bolts the 50 several sections of covering are connected together around the boiler or pipe. The retaining-bands K are held in place around the covering by bolts J. The covering thus

formed is supported around the boiler or pipe at a short distance therefrom by the bolts N, 55 which are secured in holes provided therefor in the cross-strips H, and the inner sheet-metal lining, G, at short intervals by nuts O O. Thus it is obvious that two air-spaces are formed between the pipe and the felt—one 60 wide space, P, corresponding to the length of bolt between its head and the first nut, and a narrow space corresponding to the thickness of the second nut.

The covering for pipes may, if desired, be 65 formed in a single piece, as shown in Fig. 1, in which case it may be sprung apart at its contiguous edges R when placing it around or removing it from the pipe.

For boilers or any large area of surface the 70 covering is formed in any number of sections desired, which sections, when formed, are secured upon the surface, as mentioned, by the retaining-bands K and bolts L.

Having thus described my invention, what 75 I claim as new, and desire to secure by Letters Patent, is—

1. In a sectional or detachable covering for steam-pipes and boilers, the combination of the frame-strips H and I, arranged at right 80 angles to each other, covering B, retaining-bolts J, extending through the covering B and both of said strips H and I at their points of contact, and serving the twofold purpose of holding the parts of the frame together and 85 retaining the covering thereon, and supports N, adapted to rest upon and support the covering around and at a distance from the boiler or pipe, substantially as and for the purpose specified. 90

2. In a sectional boiler covering, the combination of the covering B, consisting of felt E, provided upon its interior and exterior surfaces with one or more sheets of paper, D and F, sheet-metal interior and exterior surfaces 95 G, frame-strips H and I, supporting-bolts N, provided with nuts O O, and retaining-bands K, provided with binding-bolts L, all substantially as and for the purpose specified.

In testimony whereof I affix my signature in 100 presence of two witnesses.

LA FAYETTE ALDRICH.
